CLAIM

The ornamental design for an electrophoresis system as shown and described.

DESCRIPTION

FIG. 1 illustrates a front, right perspective view of an electrophoresis device, showing our new design;

FIG. 2 illustrates a front, right perspective view of the electrophoresis device in exploded format to illustrate separable top and bottom components;

FIG. 3 illustrates a front elevation view of the electrophoresis device of FIGS. 1 and 2;

FIG. 4 illustrates a rear elevation view thereof;

FIG. 5 illustrates a top plan view thereof;

FIG. 6 illustrates a bottom plan view thereof;

FIG. 7 illustrates a right side elevation view thereof;

FIG. 8 illustrates a left side elevation view thereof;

FIG. 9 illustrates a top plan view of the bottom component of the electrophoresis device; and,

FIG. 10 illustrates a bottom plan view of the top component of the electrophoresis device.

In the drawings, the equal-length broken lines depict portions of the electrophoresis system that form no part of the claimed design.
